UNITED STATES PATENT OFFICE.

PAUL ADOLPHE CARTIER, OF DARNETAL, FRANCE.

MACHINE FOR MAKING PAPER BOXES.

SPECIFICATION forming part of Letters Patent No. 606,916, dated July 5, 1898.

Application filed August 25, 1897. Serial No. 649,455. (No model.)

To all whom it may concern:

Be it known that I, PAUL ADOLPHE CARTIER, a citizen of France, residing at Darne-
tal, France, have invented certain new and
useful Improvements in Machines for Mak-
ing Paper Boxes, of which the following is a
specification.

As is well known in the manufacture of
boxes of paper, cardboard, &c., and in par-
ticular in the manufacture of boxes of round,
oval, or analogous shapes, the material em-
ployed sometimes becomes creased at its
edges or becomes bent in an irregular man-
ner under the action of the mechanical parts
which are designed to impart the shape to the
box which it is desired to produce. Conse-
quently the box when finished has a slovenly
appearance.

The object of this invention is to remedy
the defects above mentioned and to enable
the paper, cardboard, &c., to assume in a
more perfect manner the shape of the me-
chanical parts on which the boxes are formed.
To this end the strips of the material em-
ployed (paper, cardboard, &c.) are subjected
to a particular preparatory operation consist-
ing in milling one of the edges of the strip.
The edge thus milled is that edge which is to
be turned down in the manufacture of the
boxes for the purpose of being pasted on the
disk of cardboard, which forms either the
bottom of the box proper or the head of the
cover, according as one or the other is being
made.

The milling of the edge of the strip of pa-
per designed for the manufacture of paper
boxes is effected by the apparatus forming
the subject of this invention, which consists
of certain features of construction and com-
binations of parts to be hereinafter described
and then claimed.

In the accompanying drawings, Figure 1 is
a view in elevation of a strip of cardboard
having one of its edges milled by the machine
forming part of my invention. Fig. 2 is a
vertical central section of a box constructed
by my machine. Fig. 3 is a perspective view
of the box. Fig. 4 is a front elevation of the
machine. Fig. 5 is a side elevation, and Fig.
6 is a plan thereof. Fig. 7 is a fragmental
view showing in perspective the manner in
which the machine is adjusted upon its sup-

port. Figs. 8, 9, and 10 are side, top, and
end views of details of construction.

Similar letters of reference indicate corre- 55
sponding parts.

As shown in the accompanying drawings,
the apparatus consists essentially of two mill-
ing-wheels A and B, Fig. 4. The teeth of the
millings-wheels may have any suitable form. 60
They may be straight or inclined, narrow or
wide. The millings-wheel B is mounted on a
shaft situated inside a sleeve C, fixed by a
screw D on the frame E of the apparatus.
This millings-wheel rotates simply in conse- 65
quence of the rotation of the other millings-
wheel A, with which it gears. The millings-
wheel A is mounted loosely on the shaft F,
which carries at its lower part a bevel-wheel
f, gearing with another bevel-wheel f', mount- 70
ed on the shaft G, which receives rotary mo-
tion by means of a power-driven sprocket-
chain H. A milled nut I, screwed on the
threaded upper part of the shaft F, binds the
wheel A to the shaft F, so as to cause it to ro- 75
tate with the same.

The frame E, Fig. 4, which carries all the
parts above mentioned, is provided with a
slotted and grooved extension J, which is ad-
justably secured to the part K of the support, 80
Fig. 7, by means of a rib engaging said groove.
A threaded bolt carried by the part K passes
through the slot formed in the extension J
and is provided with a binding-nut by which
the parts are locked in their adjusted posi- 85
tion. Integral with the part K of the sup-
port is a slotted part L, horizontally arranged
thereto and provided with a groove which al-
lows the apparatus to be shifted horizontally
along a bar or straight edge M, Fig. 4, fixed 90
upon the framing of the machine in which the
paper strips are to be used for the manufac-
ture of the boxes on leaving the millings ap-
paratus just described. Binding-bolts carried
by the said edge M extend through the slots 95
of the part L and permit the locking of the
parts in their adjusted position.

The paper strip, one of whose edges is to
be milled, must be guided during the action
of the millings-wheels A and B. For this pur- 100
pose a guideway for the paper strip is com-
posed of a rectangular bracket m, which is
supported on an upright plate o. On this
bracket are mounted two plates of copper m'

m^2 , which are bent at an angle corresponding to the rectangular bracket m in such a manner that their horizontal portions rest on the horizontal portion of the bracket, while between the vertical portion of the plates and the vertical portion of the bracket m is left a small space m^3 . The copper plates $m' m^2$ are bent at their upper ends over the edge of the vertical portion of bracket m , as shown at m^4 , which bent-over portion has a bearing on the upper edge of the bracket. In this manner a guideway is obtained for the paper strip between the vertical portions of the bracket and the copper plate.

15 The recess n is located midway of the guideway formed by the angular bracket and angular plates $m' m^2$, into which recess extend the intermeshing gear-wheels by which the forward feed of the paper strip is produced.

20 The recess n has to be of sufficient size for permitting the proper intermeshing of the gear-wheels. The horizontal portions of the copper plates $m' m^2$ are provided with slots by which they may be adjusted along a screw-

25 post x and clamped by thumb-nuts y . By means of the slotted portions and the screws the curved plates may be adjusted farther away or closer to each other, so as to change the length of the recess n , according to requirement.

30 The edge of the paper strip can thus be subjected to the action of the milling-wheels A and B during its passage through the guideway and be gripped between these two milling-wheels, which gear one with the other, while having sufficient play to allow of the passage of the paper strip. Obviously it is necessary to regulate the height of the guideway according to the width of the milled part to be produced and also according to the

35 depth of the strips used. For this purpose

the bracket m , Fig. 8, is supported by a rod O , Figs. 4 and 8, which is adapted to be fixed upon the frame E of the apparatus by means of a fixing-bolt O'' , passing in an elongated hole O' .

45

In the manufacture of boxes with milled strips the disks designed to constitute the bottom of the box and the head of the lid are not milled. It is only the strips which are designed to be turned down over the said bottom and head which are subjected to the milling operation.

50

Having thus described my invention, I claim as new and desire to secure by Letters Patent—

55

1. In a machine for making paper boxes, the combination with a vertically and horizontally adjustable frame, of a milling-wheel loosely mounted in said frame, a power-driven shaft, a milling-wheel fixed upon said shaft 60 and loosely meshing with said loosely-mounted milling-wheel, and a vertically-adjustable guideway located between said milling-wheels, substantially as set forth.

2. In a machine for making paper boxes, 65 the combination with a suitable frame, milling-wheels carried by said frame and means for operating said milling-wheels, of a guideway constructed of a rectangular bracket provided with a central recess, adjustable plates 70 carried by said bracket and shaped to conform therewith, and means for vertically adjusting said bracket, substantially as set forth.

In testimony whereof I have signed this specification in the presence of two subscribers.
